UNITED STATES PATENT OFFICE.

JAMES KENYON, OF BOLTON, ENGLAND.

LIFTING-BAR OF MOLDING-BOXES.

1,301,850.

Specification of Letters Patent. Patented Apr. 29, 1919.

Application filed February 11, 1919. Serial No. 276,264.

To all whom it may concern:

Be it known that I, JAMES KENYON, iron moulder, of Bolton, in the county of Lancaster, England, have invented certain new and useful Improvements Relating to the Lifting-Bars of Molding-Boxes, of which the following is a specification.

This invention relates to molding boxes and to the provision of lifting bars therefor. 10 The object of the invention is to provide a removable lifting bar which may be applied at different predetermined places on a molding box intended to receive the same.

A further object of the invention is to 15 adapt such removable lifting bar for use with molding boxes of the known type from which one or more of the usual integral lifting bars have been broken.

Reference being made to the annexed 20 drawing,

Figure 1 is a plan of a molding box made according to the present invention, showing two of the improved lifting bars applied thereto.

25 Fig. 2 is a similar plan of a molding box of the known construction from which two of the lifting bars have been broken away and replaced by the improved lifting bar of the present invention.

30 Fig. 3 is a cross section on the line 3—3 of Fig. 2.

Fig. 4 is a cross section on line 4—4 of Fig. 1 or Fig. 2.

35 Fig. 5 is a perspective view on a larger scale showing part of the molding box, and of the improved lifting bar and the means for securing the latter in place.

According to the present invention the lifting bar A is adapted to engage at its ends 40 with projections B on the interior face of the sides B¹ of the molding box. For this purpose the ends of the lifting bar A may conveniently be provided with V-shaped notches A¹ to engage correspondingly shaped projecting ribs B on the sides of the molding 45 box.

This construction readily permits of the improved lifting bar A being used in replacement of a broken fixed lifting bar such 50 as C in a molding box of the usual known construction, since the broken bar may be filed or cut away so as to leave only two projecting V shaped ribs at the ends where it previously joined to the sides of the molding 55 box.

The improved lifting bar is formed also with two bosses D located respectively at a short distance from its ends. Into each such boss is securely molded one leg E¹ of a wrought iron cramp E which is adapted to 60 extend over and beyond the edge of the molding box and is provided with a dependent leg E² preferably broadened in the form of a plate E³ parallel to and at a small distance from the outside face of the sides of 65 the molding box. A wedging member such as F driven between the plate E³ and the outside face of the molding box serves to secure the end of the lifting bar firmly but removably in place. 70

What I claim as my invention and desire to secure by Letters Patent of the United States is:—

1. The combination with a molding box having projections on the inner face of its 75 side walls, of a lifting bar adapted to engage said projections, cramps extending from said lifting bar bridging the sides of the molding box and means for wedging said cramps.

2. The combination with a molding box 80 of a lifting bar having bearing against the inner face of the sides of the molding box, cramps bridging said sides and means for securing said cramps on the sides.

3. A molding box lifting bar comprising 85 two cramps extending beyond the ends thereof and having returned portions spaced from said ends.

4. A molding box lifting bar comprising 90 bosses, cramps having legs engaging said bosses and other legs spaced from the ends of the lifting bar.

5. A molding box lifting bar comprising 95 bosses, and cramps having legs engaging said bosses, said cramps extending beyond the ends of the lifting bar and other legs depending parallel to the ends of the lifting bar but spaced therefrom.

6. A molding box lifting bar having 100 notches in its ends, bosses inward of said ends cramps engaging said bosses and returned beyond the said ends.

In witness whereof I have signed this specification in the presence of two witnesses.

JAMES KENYON.
